Attorney.*

UNITED STATES PATENT OFFICE.

WILLIAM A. NEWMAN, OF MONTREAL, QUEBEC, CANADA.

LOCOMOTIVE.

1,354,679.

Specification of Letters Patent.

Patented Oct. 5, 1920.

Application filed September 9, 1919. Serial No. 322,765.

To all whom it may concern:

Be it known that I, WILLIAM A. NEWMAN, of Notre Dame de Grace, in the city of Montreal, Province of Quebec, Dominion of Canada, a subject of the King of Great Britain, have invented certain new and useful Improvements in Locomotives; and I do hereby declare that the following is a full, clear, and exact description thereof.

10 My invention relates particularly to the connection between the cylinder and the engine frame.

Heretofore the fastening employed for connecting the cylinders to the frame was such that an abnormal amount of twisting and bending was set up at a point where the cylinders are solidly fastened to the frame, which has resulted in a large amount of breakage at this point, and consequently, in 15 many cases, accidents. This breakage always necessitates the withdrawal of the locomotive from service. Another defect in the construction heretofore used was that the extreme variations in climatic conditions are 20 not adequately taken care of. Changes in atmospheric temperature cause great stresses in the locomotive frame because, while the boiler and cylinders remain hot at all outside temperatures, and the parts of the 25 frames to which they are connected keep correspondingly hot, comparatively speaking, that portion of the frame farther away from the boiler connection, near the driving wheels for instance, is reduced in temperature to practically that of the atmosphere, 30 which in some localities is as low as 60° below zero in winter. This difference in temperature in different parts of the frame and the consequent difference in contraction and 35 expansion results in the above mentioned 40 stresses.

My invention has for its object to take care of these stresses due to both twisting and bending of the frame, while the engine 45 is running, and the expansion and contraction due to changes in atmospheric temperature, by deflecting strains of contraction and expansion to parts of the structure away from the connections, and thereby entirely eliminating loose cylinders and practically entirely eliminating frame breakage.

To this end the invention consists of a particular construction of the frames of the locomotive with extension lugs disposed to 50 coact with vertical lugs upon the back-wall

of the cylinder and a pair of reinforcement castings, the cylinder casting having brackets to which the lugs of the engine frames are fastened, and longitudinal central lugs to which one side of each casting is fastened, 60 the opposite sides being fastened to the engine frames. This combination and particular arrangement of parts provides means whereby the heavy stresses above mentioned are absorbed and distributed, and frame 65 breakage is eliminated at the point.

For full comprehension of my invention reference must be had to the accompanying drawings in which—

Figure 1 is a transverse vertical sectional 70 view of the main frames of a locomotive taken behind the cylinders;

Fig. 2 is a detail longitudinal vertical sectional view taken on line 2—2, Fig. 1;

Fig. 3 is a detail fragmentary sectional 75 view of the back wall of the casting cylinder illustrating one of the lugs formed integrally therewith;

Fig. 4 is a plan view of one of the reinforcement castings; 80

Fig. 5 is a side elevation thereof as viewed from the same angle as Fig. 2; and

Fig. 6 is an end elevation of this casting.

The engine's main-frames are indicated at 85 *bb*, the cylinder-castings or saddle at *d* and the cylinders at *e* and *f*. The zone of great distortion due to extreme variations in temperature between parts of the cylinder castings and frames is where the frames are fastened immediately adjacent to the cylinder 90 castings, and it is this distortion that causes practically all frame breakage and loose cylinders. My invention overcomes this serious defect by constructing the cylinder castings with brackets *gg*, the lower ends of 95 which are formed integrally with horizontal flange *c*, and engine frames with forwardly extending lugs *h* bolted or otherwise rigidly fastened to the brackets *g*. To further absorb the stress and more securely fasten the 100 cylinder castings to the frame the cylinder casting has a series of downwardly extending lugs *i* along the under-side of its center line, and a pair of reinforcement members are bolted or otherwise rigidly fastened between the engine frames, the cylinder castings and the lugs *i*. These reinforcement members are of right and left hand design, 105 and each consists of a plate-like part *j*, *k*, *l*, forming three sides including a right angle, 110

(the two sides *j* and *k*), while the third side *l* is bent obtusely to side *k* to conform to one side of each of the lugs *i*. For certain types of locomotives the side *l* terminates at the 5 lugs *i*, whereas for other types as in the embodiment illustrated the side *l* is extended downwardly below the level of the side *j* and terminates in an arm *m*. The top side *k*, side *j* and the obtuse portion of side *l* 10 are braced together by a pair of webs *nn* while the arm *m* is braced by a pair of ribs *o*. These members are bolted in the space between the under-side of the cylinder castings and the engine frames, the top sides *k* 15 of the members being bolted or otherwise rigidly fastened as at *p* to the flange *c* and bottom web *c*¹ of the cylinder castings. The sides *j* are bolted or otherwise rigidly fastened to the engine frame and flange *qq* of 20 the cylinder castings. These fastenings are preferably a series of bolts extending through the sides *j*, the frames and the flanges *q*, while the sides *l* are rigidly secured to the lugs *i* by through-bolts *r*. These 25 reinforcement members are preferably castings although they may be forgings within the spirit of my invention or be cast integral with the frame. This particular construction and arrangement of parts provides 30 for the absorption of the stresses arising from extreme variations in temperature due to different climatic conditions met in service, and this result is obtained by the fact of the holding power of the particular design 35 of the castings including the continuous cross-brace between the engine frames presented by the webs *n*, the lugs *i* and sides *j* co-acting with the flanges *q* and the brackets *g* and lugs *h*.

40 4. What I claim is as follows:

1. In a locomotive the combination with 45 a pair of spaced main frames and a cylinder saddle, the latter having a depending portion along the longitudinal center of its underside and substantially midway between the frames, of reinforcement means relatively bracing the frames and cylinder saddle, said means being secured to the underside of the saddle and to the frames and 50 bearings between the latter and the said depending portion.

2. The combination with the cylinder saddle and main frames of a locomotive, the main frames presenting substantially vertical sides, of reinforcement means separate and distinct from the cylinder saddle and relatively bracing the frames and frames and cylinder saddle, such means consisting of a pair of reinforcement members rigidly 55 secured between the engine frames and the under side of the cylinder saddle and bearing against the vertical sides of the frames.

3. The combination with the cylinder casting and main frames of a locomotive, of 60 means relatively bracing the frame and back

wall of the cylinder castings, such last mentioned means consisting of brackets integrally formed upon the said back wall and forwardly extending lugs upon the engine frames and rigidly secured to the said 70 brackets.

4. The combination with the cylinder casting and main frames of a locomotive, of reinforcement means relatively bracing the frames and frames and casting and means 75 relatively bracing the frame and back wall of the cylinder castings, such last mentioned means consisting of brackets integrally formed upon the said back wall and forwardly extending lugs upon the engine 80 frames and rigidly secured to the said brackets.

5. The combination with the cylinder casting and main frames of a locomotive, of reinforcement means relatively bracing the 85 frames and frames and casting, such means consisting of reinforcement members rigidly secured between the engine frames and the under side of the casting, and means relatively bracing the frames and the back 90 wall of the castings, such last mentioned means consisting of brackets integrally formed upon the said back wall and rearwardly extending lugs upon the engine frames and rigidly secured to the said 95 brackets.

6. In a locomotive the combination of main frames and cylinder casting, the latter having a plurality of downwardly extending tapered lugs along the longitudinal center of its underside; a pair of reinforcement members each consisting of two sides in right angular relation and a side in obtuse angular relation opposite one of the first mentioned sides, the opposite sides being relatively braced, means securing the obtuse angular sides of the member to opposite sides of the tapered lugs; means rigidly securing the remaining sides to the engine frames and cylinder casting. 105

7. In a locomotive the combination of main frames and cylinder casting, the latter having a plurality of downwardly extending tapered lugs along the longitudinal center of its under side; a pair of reinforcement members each consisting of two sides in right angular relation and a side in obtuse angular relation opposite one of the first mentioned sides, the opposite sides being relatively braced by webs, means securing the obtuse angular sides of the members to opposite sides of the tapered lugs; means rigidly securing the remaining sides to the engine frames and cylinder casting; the back wall of the cylinder castings having a pair of brackets and the frames having forwardly extending lugs, and means rigidly securing the last mentioned lugs to the brackets. 115

8. In a locomotive the combination of 120

main frames and cylinder casting, the latter having a plurality of downwardly extending tapered lugs along the longitudinal center of its under side; a pair of reinforcement members each consisting of two sides in right angular relation, and a side in obtuse angular relation opposite one of the first mentioned sides, such last mentioned side having an extension in the form of an arm, 5 and the opposite sides being relatively braced by webs, means securing the obtuse angular sides of the members to opposite sides of the tapered lugs; means rigidly securing the remaining sides to the engine frames and cylinder casting. 10

15 frames and cylinder casting.

9. In a locomotive the combination of main frames and cylinder casting, the latter having a plurality of downwardly extending tapered lugs along the longitudinal center of its under side; a pair of reinforcement members each consisting of two sides 20

in right angular relation and a side in obtuse angular relation opposite one of the first mentioned sides, such last mentioned side having an extension in the form of an arm, 25 and the opposite sides being relatively braced by webs, means securing the obtuse angular sides of the members to opposite sides of the tapered lugs; means rigidly securing the remaining sides to the engine frames and cylinder casting; the back wall of the cylinder castings having a pair of brackets and the frames having rearwardly extending lugs, and means rigidly securing the last mentioned lugs to the brackets. 30

35 In testimony whereof I have signed my name to this specification in the presence of two witnesses.

WILLIAM A. NEWMAN.
